EXTRACTING TOOL

Harold Caminez, Kew Gardens, N. Y., assignor to
 Aircraft Screw Products Company, Inc., Long
 Island City, N. Y., a corporation of New York

Application January 24, 1939, Serial No. 252,557

2 Claims. (CL. 81—71)

The present invention relates to a tool for extracting a wire coil embedded in the thread groove of a female screw member as described in my copending applications Ser. Nos. 91,263, 190,-168, and 246,814, filed July 18, 1936, Feb. 12, 1938, and Dec. 20, 1938, respectively. In the removing of such coils from their seats in thread grooves difficulties are encountered, because the coil tends to expand and thus to wedge in the thread groove so much so that any torque to remove the coil is counteracted by friction.

The object of the present invention is the provision of a tool for facilitating the removal of such coil, and the invention mainly consists in a tapered instrument adapted to grip the first convolution from the interior of the coil, and to apply thereto a torque in such a sense as to screw the coil out of the thread groove. In this manner, the second and the following convolution will contract and readily follow the movement of the tool.

Further details and objects of the invention will be apparent from the description hereinafter and the appended drawing illustrating an embodiment thereof by way of example.

In the drawing, Fig. 1 is a side elevation of the tool; Fig. 2, a sectional view along line 2—2 of Fig. 1, and Fig. 3, a sectional view of a female threaded member with a wire coil therein and the new extracting tool applied for removal of the coil.

Referring now to the drawing the tool consists of a head portion 1, a shank portion 2 and a tapered end portion 3. The top portion is provided with a means, e. g. handle 4, for applying a torque about the longitudinal axis 5. The end portion 3 is tapered and has at least one sharp edge intended to engage with the first convolution of a coil. In the preferred embodiment the portion 3 has a four cornered cross-section as shown in Fig. 2. Two corners 6 are hook-like projecting from the substantially rectangular cross-sectional area and are sharpened so as to grip the coil securely when the tool is used. For the removal of a wire coil 7 embedded in the thread groove 8 of a female member 9 as shown in Fig. 3, the tool is pushed with its end portion 3 into the coil so that the corners 6 bite into the first convolution 10 of the coil. By turning the tool in such a sense as to screw the coil out of the thread groove 8, all convolutions will be contracted owing to the friction between the coil and the female member 9, except the first convolution which is spread by the tool proper. Thereby the

friction is sufficiently reduced for an easy removal of the coil.

I have found that the illustrated form of the tool gives the best results in removing wire coils of the type described in virtue of the following prevailing conditions: In general, the wire is made of a hard material, but because of its shape is fairly resilient. It is, therefore, necessary that the extracting tool be so designed that it can imbed itself into the hard wire without causing much radial pressure between the hard wire and the thread groove in which it is fed. If much radial pressure is exerted, and particularly if such pressure is exerted simultaneously at many points of the periphery of one convolution, the hard wire and especially its end, will catch into the softer threaded groove thereby damaging the tapped hole. One pair of diametrically opposed edges, therefore, produces the best results. On the other hand, a tool having only two edges such as a double-edged blade would not be satisfactory because of the lack of stiffness of a coil portion screwed out of the threaded member with the aid of the extracting tool.

In order to overcome this difficulty the non-cutting portions preferably in the shape of relatively blunt edges 6' intermediate the sharp edges 6 are provided on a slightly smaller distance from the tool axis than the last-mentioned edges, as clearly shown in Fig. 2. Now, it will be apparent that the coil-convolutions contracted by the torque which is applied through the edges 6 will bear not only against the latter but also against the edges 6'. In this manner, the extracted portion of the coil will be sufficiently supported to transmit the extracting force to the convolutions which are still embedded in the thread groove. The blunt edges offer the additional advantage that they guide the tool so as to engage the coil with its two cutting edges at approximately diametrically opposite points.

What I claim:

1. An extracting tool for the removal of a wire coil embedded in the thread groove of a female screw member comprising a shank portion and a tapered end portion, and means for applying a torque about the longitudinal axis of the tool, said tapered end portion including two projecting cutting edges diametrically opposite each other, and two non-cutting portions intermediate said cutting edges, said non-cutting portions being arranged on a smaller diameter than the cutting edges but at such a distance from the shank axis that coil convolutions contracted by said tool ap-

plied thereto may bear against said non-cutting portions.

2. An extracting tool for the removal of a wire coil embedded in the thread groove of a female screw member comprising a shank portion and a tapered end portion, and means for applying a torque about the longitudinal axis of the tool, said tapered end portion having a substantially

square cross-section, the ends of the opposite sides of the square, at one pair of diametrically opposed corners, projecting slightly beyond the outline of a true square, and the adjacent ends of the other pair of sides being curved so as to form hollow cutting edges with said projecting ends respectively.

HAROLD CAMINEZ.
